UNITED STATES PATENT OFFICE.

PABLO PARIS, OF NEW YORK, N. Y.

MOTOR-DRIVE FOR TYPESETTING-MACHINES.

1,339,667.

Specification of Letters Patent. Patented May 11, 1920.

Application filed August 13, 1919. Serial No. 317,114.

To all whom it may concern:

Be it known that I, PABLO PARIS, a citizen of the Republic of Venezuela, and resident of New York city, in the county of New York and State of New York, have invented certain new and useful Improvements in Motor-Drives for Typesetting-Machines, of which the following is a specification.

10 This invention relates to typesetting machines, especially of the character set forth in U. S. Patent No. 1,259,900, granted to myself March 19, 1918.

15 The object of the present invention is to provide a motor drive for a machine of this character, that will serve to convey a type selected by the depression of a key, to the chase in which the type are placed in series to produce the desired printing effect.

20 In the accompanying drawings showing one embodiment of my invention, Figure 1 is a side elevation, showing part of the keyboard and conveying means, and selecting means.

25 Figs. 2, 3, 4 and 5 are similar views showing the parts in successive positions.

Fig. 6 is a plan showing the two conveying mechanisms.

30 Fig. 7 is a vertical section through a portion of the mechanism.

In the drawings, 2 indicates a keyboard having keys 3 that when depressed each engages a universal bar 4 carried by levers 5 pivoted at 6. By mechanism not herein set forth each key co-operates with a selecting mechanism, denoted generally by 7, by which a type corresponding with the key depressed is selected and advanced to a suitable guide-way, to be conveyed by suitable 40 conveying means. Selecting means of this character are set forth in detail in my said patent.

Any suitable means or mechanism for conveying the selected type can be employed, I illustrate a conveying device that is in the form of extensible and contractible means, such as a lazy-tong device denoted by 8. This device is also set forth in my said patent, and is actuated by means of 45 links 9 and 10 pivoted to a cross arm 11. This arm is connected with a lever 12, that is rocked from a motor shaft 13, through suitable connecting and driving mechanism.

50 The shaft 13 carries a clutch cone 14 that is keyed to slide thereon and carries a collar 15 slidable on the shaft and having a screw

threaded bore 16 that engages a screw threaded sleeve 17 fast to the shaft frame and forms a bearing for shaft 13. The swinging of the sleeve 15 by an arm 18 will 60 advance the cone 14 into clutch sleeve 19 fast on a sleeve 20 loose on the shaft 13.

The sleeve 20 carries an elliptical gear 21 that meshes with an elliptical gear 22 fast on a short shaft 23. The latter shaft 65 carries a disk 24 having a crank pin 25 thereon, that connects with the said lever 12; a rod 26 connects this crank pin with the said lever 12. By this means each rotation of shaft 23 will rock the arm 12 and 70 links 9 and 10, causing the lazy-tong to expand to feed a selected type, and then contract to normal position, as indicated in Figs. 1 and 4.

By reason of the elliptical gear connecting the driving shaft with the shaft 23, at the beginning of a revolution, from the position of Fig. 1, the shaft 23 will have a relatively accelerated movement for the first half of the revolution, and for the balance 80 of one revolution the shaft 23 will have a gradually retarded relative movement. This would result in the lazy-tong device increasing its speed from the start, and decreasing its speed at the end of the return 85 movement. But the crank connections between the shaft 23 and the lazy-tong device will result in an accelerated starting movement, that becomes retarded at the end of the half revolution as the crank pin reaches 90 a dead center. Therefore the lazy-tong device will have a retarded movement at the end of the advance stroke. As the crank pin continues its rotation it will increase the speed of the lazy-tong device, and at the 95 latter portion of the revolution will retard the movement, so that the lazy-tong device will have its speed much slower at the end of the return movement.

I further provide means whereby the 100 shaft 13, that can be driven continuously, as by an electric motor, is connected through the clutch to impart a single revolution to the sleeve 20, and is thereupon disconnected, and which is effected by depression of the 105 universal bar 4. The arm 18 that serves to advance the clutch cone and retract it, is connected by a bar 27 with a lever 28 swinging loose on the shaft 6. A lever 32 fast with arms 5 on shaft 6 carries a block 29 110 that engages the pivot pin 30 of the link 27 when the universal bar 4 is depressed by

a key, and hence the arm 18 will move downward and engage the clutch member. The lever 28 projects beyond the pivot 6 and connects with a spring 31 that will elevate 5 the lever 28 and link 27 when the key is released, and hence withdraw the clutch cone 14.

I further provide means for causing the 10 clutch members to engage provided the key is not given sufficient depression to advance the clutch cone, to insure operation of the motor shaft to advance the conveying device. Arm 32 connects by link 33 with a lever 34, pivoted at 35, and which lever carries a pawl 36 arranged to engage a stud 37 on the clutch advancing arm 18. When the key is fully depressed, see Figs. 2 and 3, the pawl 36 will be positioned some distance above the stud 37, and if the key is depressed 15 but a part stroke, the pawl will still rise to engage the stud 36, see Fig. 2. A lever 38 pivoted at 39 is connected to slotted lever 34 by stud 40, and a spring 41 serves to retract levers 38 and 34 when the key and 20 universal bar are released. This will serve to draw down the pawl 36 from the position of Fig. 3, or of Fig. 2, that will carry arm 18 downward and engage the clutch members. 25

30 To release the clutch arm 18 from the pawl 36 at the end of one revolution, I arrange a cam 42 on the clutch member 19, see Fig. 4, that will strike an arm 43 connected with the pawl 36 by a link 44. This cam will swing the pawl 36 away from stud 37. Spring 45 draws pawl 36 pressed toward stud 37, also presses arm 43 against the clutch cam 42.

I also provide means for arresting the 40 rotation of the driven sleeve 20 at the end of a revolution, which comprises a stop cam 46 fast on the sleeve 20, that engages an arm 47 having a lug 48 thereon normally in position to engage this stop, see Fig. 1. 45 A link 49 connects the lever 5 with the arm 47 so that when the key and universal bar are depressed the stop arm will release the stop cam and permit rotation on engagement of the clutch members. Release of 50 the key and the rising of lever 5 will restore the stop arm 47 so that on conclusion of one revolution the sleeve 20 will be arrested by these parts.

It will thus be understood that when a 55 key is depressed, the selecting means will first cause a type to be advanced, and thereupon the clutch members will be shifted to engage. But the link 49 will first shift the stop arm 47 to release the sleeve 20, before 60 the clutch members engage. If the key is only partly depressed and arm 18 is not swung to advance the clutch cone sufficiently to engage, when the key is released and the universal bar rises, the pawl 36, that will 65 be raised on partial depression of a key, see

Fig. 2, will now serve to move arm 18 downward a farther distance to engage the clutch members. At the conclusion of one revolution of the sleeve 20 by the motor shaft 13, the trip cam 42 will swing pawl 36 away from the stud 37 and permit arm 18 to rise and free the clutch members. At the end of this revolution the stop arm 47, that rises as soon as the key is released, will be engaged by the stop cam 46 and arrest the 70 sleeve 20. 75

What I claim is:—

1. In a type setting machine, the combination with type selecting means, a keyboard connected with the selecting means, and means for conveying selected type, of means for actuating the conveying means, comprising a motor with a continuously rotating shaft, a clutch device having connections with the motor shaft and with the advancing means whereby on actuation of any key, after the key has operated the selecting means, the motor will actuate the conveying means, and means for releasing the clutch when the conveying means has advanced the 80 selected type and returned to normal position. 85

2. In a type setting machine, the combination with type selecting means, a keyboard connected with the selecting means, and means for conveying selected type, of means for actuating the conveying means, comprising a motor with a continuously rotating shaft, a clutch device having connections with the motor shaft and with the advancing means whereby on actuation of any key, after the key has operated the selecting means, the motor will actuate the conveying means, and means for releasing the clutch when the conveying means has advanced the 95 selected type and returned to normal position, said clutch connections including 100 means whereby the said conveying means is first given an accelerated movement and then given a retarded movement. 105

3. In a type setting machine, the combination with type selecting means, a keyboard connected with the selecting means, and means for conveying selected type, of means for actuating the conveying means, comprising a motor with a continuously rotating shaft, a clutch device having connections with the motor shaft and with the advancing means whereby on actuation of any key, after the key has operated the selecting 110 means, the motor will actuate the conveying means, and means for releasing the clutch when the conveying means has advanced the selected type and returned to normal position, said clutch connections including 115 means whereby the said conveying means is first given an accelerated movement and then given a retarded movement during the 120 advance stroke of the conveying means, and also given an accelerated movement and 125 130

then a retarded movement during the return stroke of the conveying means.

4. In a type setting machine, the combination with type selecting means, a keyboard connected with the selecting means to select a type on depression of any key, and means for conveying a selected type, of means for actuating the conveying means, comprising a motor with a continuously rotating shaft, a clutch device having connections with the conveying means and with the motor shaft whereby on retraction of a depressed key, the motor will actuate the conveying means, and means for releasing the clutch when the conveying means has advanced the selected type and returned to normal position.

5. In a type setting machine, the combination with type selecting means, a keyboard connected with the selecting means to select a type on depression of any key, and means for conveying a selected type, of means for actuating the conveying means, comprising a motor with a continuously rotating shaft, a clutch device having connections with the conveying means and with the motor shaft whereby on retraction of a depressed key, the motor will actuate the conveying means, and means for releasing the clutch when the conveying means has advanced the selected type and returned to normal position.

20 6. In a type setting machine, the combination with type selecting means, a keyboard connected with the selecting means to select a type on depression of any key, and means for conveying a selected type, of means for actuating the conveying means, comprising a motor with a continuously rotating shaft, a clutch device having connections with the conveying means and with the motor shaft whereby on retraction of a depressed key, the motor will actuate the conveying means, and means for releasing the clutch when the conveying means has advanced the selected type and returned to normal position, said clutch connections including means whereby the said conveying means is first accelerated and then given a retarded movement.

25 7. In a type setting machine, the combination with type selecting means, a keyboard connected with the selecting means to select a type on depression of any key, and means for conveying a selected type, of means for actuating the conveying means, comprising a motor with a continuously rotating shaft, a clutch device having connections with the conveying means and with the motor shaft whereby on retraction of a depressed key, the motor will actuate the conveying means, and means for releasing the clutch when the conveying means has advanced the selected type and returned to normal position, said clutch connections including means whereby the said conveying means is first accelerated and then given a retarded movement during the advance stroke of the conveying means, and also given an accelerated and then a retarded movement during the return stroke of the conveying means.

30 8. In a type setting machine, the combination with type selecting means, a keyboard connected with the selecting means, and means for conveying selected type, of means for actuating the conveying means, comprising a motor with a continuously rotating shaft, a clutch device having connections with the motor shaft and with the advancing means whereby on actuation of any key, after the key has operated the selecting

means, the motor will actuate the conveying means, and means for releasing the clutch when the conveying means has advanced the selected type and returned to normal position, said clutch connections including 70 elliptical gearing whereby the said conveying means is first given an accelerated movement and then given a retarded movement.

8. In a type setting machine, the combination with type selecting means, a keyboard 75 connected with the selecting means, and means for conveying selected type, of means for actuating the conveying means, comprising a motor with a continuously rotating shaft, a clutch device having connections with the motor shaft and with the advancing means whereby on actuation of any key, after the key has operated the selecting means, the motor will actuate the conveying means, and means for releasing 80 the clutch when the conveying means has advanced the selected type and returned to normal position, said clutch connections including elliptical gearing and a crank movement whereby the said conveying means is 85 first given an accelerated movement and then given a retarded movement during the advance stroke of the conveying means, and also given an accelerated movement and then a retarded movement during the return 90 stroke of the conveying means.

9. In a type setting machine, the combination with type selecting means, a keyboard connected with the selecting means, and means for conveying selected type, of means 100 for actuating the conveying means, comprising a motor with a continuously rotating shaft, a clutch device having connections with the motor shaft and with the advancing means whereby on actuation of any key, 105 after the key has operated the selecting means, the motor will actuate the conveying means, and means for releasing the clutch when the conveying means has advanced the selected type and returned to normal position, said clutch connections including 110 an elliptical gearing whereby the said conveying means is first given an accelerated movement during the advance movement and return movement of the conveying 115 means, and a crank movement that will cause a retarded movement at the final portion of the advance and of the return stroke of the conveying means.

10. In a type setting machine, the combination with type selecting means, a keyboard connected with the selecting means, and a reciprocating extensible and contractible device for conveying selected type, of means for actuating the conveying means, 120 comprising a motor with a continuously rotating shaft, a clutch device having connections with the motor shaft and with the reciprocating device whereby on actuation of any key, after the key has operated the se- 130

lecting means, the motor will reciprocate the conveying means, and means for releasing the clutch after one reciprocation of the conveying means.

- 5 11. In a type setting machine, the combination with type selecting means, a keyboard connected with the selecting means, and a reciprocating extensible and contractible device for conveying selected type, of
10 means for actuating the conveying means, comprising a motor with a continuously rotating shaft, a clutch device having connections with the motor shaft and with the reciprocating device whereby on actuation of
15 any key, after the key has operated the selecting means, the motor will reciprocate the conveying means, and means for releasing the clutch after reciprocation of the conveying means, said clutch connections including means whereby the said conveying means is first given an accelerated movement when advanced and then given a retarded movement when retracted.
20 12. In a type setting machine, the combination with type selecting means, a keyboard connected with the selecting means, and a reciprocating extensible and contractible device for conveying selected type, of means for actuating the conveying means,
25 comprising a motor with a continuously rotating shaft, a clutch device having connections with the motor shaft and with the reciprocating device whereby on actuation of any key, after the key has operated the selecting means, the motor will reciprocate the conveying means, and means for releasing the clutch after one reciprocation of the conveying means, said clutch connections including means whereby the said reciprocating means is first given an accelerated movement and then given a retarded movement during the advance stroke, and also given an accelerated movement and then a retarded movement during the return stroke.
30 13. In a type setting machine, the combination with type selecting means, means for advancing selected type, and a keyboard connected with the selecting means, of means for actuating the advancing means, comprising a motor with a continuously rotating shaft, a shaft carrying a clutch member, a clutch member on the motor shaft arranged to engage said clutch member, a universal bar depressed by any of the keys, a lever swung by the universal bar, a spring pawl on said lever, an arm on said clutch member arranged to be engaged by said pawl when swung on movement of said lever from a key depressed whereby to engage the clutch members, a cam on the motor shaft arranged to engage said pawl to trip it from the clutch member when the clutch shaft has made one revolution, a stop on the clutch shaft, a swinging lever arranged to engage said stop when the clutch
35 60 65

shaft has made one revolution and tripped the clutch member, a connection from the universal bar lever and said stop lever to swing the lever and release the stop on depression of the universal bar, and connections between the clutch shaft and the advancing means to cause a reciprocation of the advancing means for each revolution of the clutch shaft.

14. In a type setting machine, the combination with type selecting means, means for advancing selected type, and a keyboard connected with the selecting means, of means for actuating the advancing means, comprising a motor with a continuously rotating shaft, a shaft carrying a clutch member, a clutch member on the motor shaft arranged to engage said clutch member, a universal bar depressed by any of the keys, a lever swung by the universal bar, a spring pawl on said lever, an arm on said clutch member arranged to be engaged by said pawl when swung on movement of said lever from a key depressed whereby to engage the clutch members, a cam on the motor shaft arranged to engage said pawl to trip it from the clutch member when the clutch shaft has made one revolution, a stop on the clutch shaft, a swinging lever arranged to engage said stop when the clutch shaft has made one revolution and tripped the clutch member, a connection from the universal bar lever and said stop lever to swing the lever and release the stop on depression of the universal bar, an elliptical gear on the clutch shaft, a second shaft carrying an elliptical gear meshing with said gear, a crank arm on the second shaft, a lever connected with the reciprocating conveying means, and a connecting rod between said latter lever and said crank.

15. In a type setting machine, the combination with type selecting means, means for advancing selected type, and a keyboard connected with the selecting means, of means for actuating the advancing means, comprising a motor with a continuously rotating shaft, a shaft carrying a clutch member, a clutch member on the motor shaft arranged to engage said clutch member, a universal bar depressed by any of the keys, a lever swung by the universal bar, a spring pawl on said lever, an arm on said clutch member arranged to be engaged by said pawl when swung on movement of said lever from a key depressed whereby to engage the clutch members, a cam on the motor shaft arranged to engage said pawl to trip it from the clutch member when the clutch shaft has made one revolution, a stop on the clutch shaft, a swinging lever arranged to engage said stop when the clutch shaft has made one revolution and tripped the clutch member, a connection from the universal bar lever and said stop lever to

swing the lever and release the stop on depression of the universal bar, said type advancing means comprising an extensible and contractible device and connections between the latter device and said clutch shaft to reciprocate the device for each revolution of the shaft.

16. In a type setting machine, the combination with type selecting means, means for advancing selected type, and a keyboard connected with the selecting means, of means for actuating the advancing means, comprising a motor with a continuously rotating shaft, a shaft carrying a clutch member, a clutch member on the motor shaft arranged to engage said clutch member, a universal bar depressed by any of the keys, a lever swung by the universal bar, a spring pawl on said lever, an arm on said clutch member arranged to be engaged by said pawl when swung on movement of said lever from a key depressed whereby to engage the clutch members, a cam on the motor shaft arranged to engage said pawl to trip it from the clutch member when the clutch shaft has made one revolution, a stop on the clutch shaft, a swinging lever arranged to engage said stop when the clutch shaft has made one revolution and tripped the clutch member, and a connection from the universal bar lever and said stop lever to swing the lever and release the stop on depression of the universal bar, an elliptical gear on the clutch shaft, a second shaft carrying an elliptical gear meshing with said gear, a crank arm on the second shaft, said type advancing means comprising an ex-

tensible and contractible device, a lever connected with said latter device, and a rod connecting said lever with said crank arm. 40

17. In a type setting machine, the combination with type selecting means, a keyboard connected with the selecting means to select a type on depression of any key, and means for conveying a selected type, of means for actuating the conveying means, comprising a motor with a continuously rotating shaft, a clutch device having connections with the conveying means and with the motor shaft whereby on depression and also on retraction of a depressed key, the motor will actuate the conveying means, and means for releasing the clutch when the conveying means has advanced the selected type and returned to normal position. 55

18. In a type setting machine, the combination with type selecting means, a keyboard connected with the selecting means to select a type on depression of any key, and means for conveying a selected type, of means for actuating the conveying means, comprising a motor with a continuously rotating shaft, a clutch device having connections with the conveying means and with the motor shaft whereby on depression of a key and also on retraction of a partly depressed key, the motor will actuate the conveying means, and means for releasing the clutch when the conveying means has advanced the selected type and returned to normal position. 60 65 70

Signed at New York city, N. Y. on Aug. 7th, 1919.

PABLO PARIS.
